(57) **CLAIM**

We claim the ornamental design for a converter for flowmeter, as shown and described.

DESCRIPTION

FIG. 1 is a front view of the design;

FIG. 2 is a back view of the design;

FIG. 3 is a plan view of the design;

FIG. 4 is a bottom view of the design;

FIG. 5 is a right side view of the design;

FIG. 6 is a left side view of the design;

FIG. 7 is a perspective view from the top of the design;

FIG. 8 is a perspective view from the right rear of the design; and,

FIG. 9 is a perspective view left rear of the design.
